UNITED STATES PATENT OFFICE.

JACOB RHULE, JR., OF PITTSBURG, PENNSYLVANIA, ASSIGNOR TO HIMSELF
AND LAWRENCE W. EBERT, OF SAME PLACE.

FEED-WATER HEATER.

SPECIFICATION forming part of Letters Patent No. 228,930, dated June 15, 1880.

Application filed February 7, 1880.

To all whom it may concern:

Be it known that I, JACOB RHULE, Jr., of Pittsburgh, in the county of Allegheny and State of Pennsylvania, have invented a new and Improved Feed-Water Heater, of which the following is a specification.

Figure 1 is a longitudinal sectional elevation on line *x x*, Fig. 2. Fig. 2 is a vertical sectional end elevation on line *y y*, Fig. 1. Fig. 3 is a vertical sectional end elevation on line *z z*, Fig. 1.

Similar letters of reference indicate corresponding parts.

The object of this invention is to provide a feed-water heater for the inside of a boiler, which heater shall serve at the same time as a depository of mud and sediment from the water, and thereby prevent scale in the boiler.

In the drawings, A represents the boiler, provided with flues B and smoke-stack C. Longitudinally within this boiler A is placed the feed-water heater, supported on legs *a a*, that rest on one of the flues B. This feed-water heater consists of a cylinder, D, provided with a water-supply pipe, E, which enters through the boiler-shell, with a steam-equalizing pipe, F, that is connected with the head of the cylinder D on a line with its bottom, and is turned upward at right angles to open into the steam-space of the boiler well above the water-line.

G is a pipe leading from the opposite end of the cylinder D, at or below the water-line thereof, and turning down at right angles nearly to the bottom of the boiler A, below the under side of the flues B.

H is the blow-off pipe of the feed-water heater, which pipe H extends horizontally from the head of the heater at its bottom, and out through the head of the boiler A, and on the end of this blow-off pipe H is fixed a cock, *d*.

Inside of the feed-water heater D, and extending downward from the top thereof to below its water-line, and between the discharge-pipe G and supply-pipe E, is the diaphragm I, whose function is to prevent the passage through the said feed-water heater of any floating substances in the water, while it serves also to retard the onward movement of the water in a measure, and to thereby cause a deposit of the sediment within the said heater.

In the top of the cylinder D, and on either side of the diaphragm I, are two openings, *f*

f, upon which are set ball-valves *g g*, which are operated by the pressure of steam within the said feed-water heater.

This heater is placed so as to be almost or entirely in the steam-space of the boiler. Consequently the water supplied to it through the pipe E will become heated by the steam in the boiler before it enters into the boiler itself through the discharge-pipe G, and the mouth of the discharge-pipe G being just over the crown-sheet of the boiler and below the flues, the entering water does not come in direct contact with the said flues.

When it is desired to blow off the sediment from the feed-water heater the valve *d* is opened, when the pressure of steam from the steam-space in the boiler A down into the pipe F will force the water and sediment from the feed-water heater out through the pipe H.

When the cock *d* is closed, steam, entering the pipe F, serves to equalize the steam-pressure in boiler and heater.

The purpose of the openings or ports *f f* and valves *g g* is also to equalize the steam-pressure in the feed-water heater with that in the boiler, should the supply of water be cut off from the heater, in which case the valves *g g* will lift and remain so until the pressure in both boiler and heater is equalized.

Having thus described my invention, what I claim as new, and desire to secure by Letters Patent, is—

1. A feed-water heater consisting of the cylinder D, placed within the steam-space of the boiler A, and provided with a supply-pipe, E, and a discharge-pipe, G, that extends below the boiler-flues to near the crown-sheet of the boiler, substantially as herein shown and described.

2. The combination, with the cylinder D, provided with supply-pipe E and discharge-pipe G, of the diaphragm I, set between said pipes, substantially as and for the purpose described.

3. In a feed-water heater set within a boiler, the steam-equalizing ports and valves *f f* and *g g*, respectively, substantially as herein shown and described.

JACOB RHULE, JR.
